UNITED STATES PATENT OFFICE.

WALTER LANE, OF HOLLAND, MICHIGAN.

PNEUMATIC AND CONNECTION FOR PNEUMATIC PIANO-PLAYERS.

1,346,900.

Specification of Letters Patent. Patented July 20, 1920.

Application filed May 19, 1917. Serial No. 169,668.

To all whom it may concern:

Be it known that I, WALTER LANE, a citizen of the United States, residing at Holland, Michigan, have invented certain new and useful Improvements in Pneumatics and Connections for Pneumatic Piano-Players, of which the following is a specification.

This invention relates to improvements in pneumatics and their connections for pneumatic piano players.

The objects of the inventions are,

First, to provide a construction of pneumatic which is readily detachable.

Second, to provide a construction of pneumatic in which the valve connection to the pneumatic is through solid parts of the structure.

Third, to provide improved detachable connections from the pneumatics to the piano action.

Fourth, to provide improved adjustable connections from the pneumatics to the piano action.

Further objects, and objects relating to details and economies of construction and operation will definitely appear from the detailed description to follow.

I accomplish the objects of my invention by the devices and means described in the following specification. The invention is clearly defined in the claims.

A structure showing a preferred embodiment of my invention is clearly illustrated in the accompanying drawing, forming a part of this specification, in which:

Figure I is a longitudinal section through the pneumatic and supporting parts, showing the connection thereof to the suction chest and showing how it is connected to the action.

Fig. II is a perspective view of the pneumatics attached to the suction chest, the suction chest being broken away, showing the openings registering with the openings in the pneumatics.

In the drawings, similar numerals of reference refer to similar parts throughout the several views.

Considering the numbered parts of the drawing, 1 represents generally a pneumatic of the bellows type comprising a relatively fixed and movable member. The movable member of the pneumatic is provided with a projecting finger 2 having a longitudinal slot 2' therein for connection to the player lifters. 3 is the pneumatic valve which is

under control through the suction tube 4, controlled by the perforated sheet at the tracker bar to which the tube 5 is connected, these parts being of the usual construction and their details forming no part of this construction they are not further illustrated.

The valve casing 3' is fixed to the upper member of the pneumatic. The pneumatic is detachably secured to the suction chest 6 so that it may be removed therefrom and from the pneumatic of the action from the front of the suction chest. The valve casing is so mounted on the pneumatic that it may be disposed against the front side of the suction chest with its ports registering therewith as shown in the drawing.

I provide the clamp or clip comprising a bar-like clamp member 7 disposed to rest on the chest 6 and a lever-like clip member 8 pivoted to the rear end of the member 7 and provided with a toe 8' engaging with the keeper 9 mounted on the pneumatic. The clip member 7 is provided with the lug 7' depending in front of the lug 11 on the valve casing so that the set screw 10 carried by the lug 7' may be adjusted to clamp the parts together. This simple arrangement provides an effective support and clamping means for the pneumatic and one which permits attachment to or removal from the suction chest without disturbing other parts.

The finger 2 of the pneumatic is designed to receive the stem 13 of the lifter or piano action actuating member 12. This stem 13 is provided with adjustable stops 14 coacting with the finger 2 and is extended through a guide 18 common to all of the stems. The guide 18 is suitably supported on the framework. The adjustable screw 15 at the upper end of the lifter or actuating member 12 contacts with the piano action. As the details of the action parts form no part of this invention, as will be readily understood, they are not described herein.

The actuating member 12 is supported and maintained in position by the horizontally disposed link 16 pivoted at one end to a suitable support and at the other to the actuating member. An adjustable stop 17 is provided to limit the upward movement of the actuating member. To limit the throw of the valve 3, an adjustable sleeve like stop 19 is provided for the port 20. This stop may be adjusted to compensate for varying thickness of leather used to face the valves.

Having thus described my invention, what I claim as new and desire to secure by Letters Patent, is:

- 5 1. In a structure of the class described, the combination with a suction chest having a port in its front side, of a pneumatic comprising a relatively fixed member disposed below said chest and having thereon a forwardly facing keeper disposed at the rear of 10 said chest, a valve casing secured to said pneumatic and disposed on the front side of said chest and provided with a port registering with the said port thereof and with an upwardly projecting lug, a clip bar disposed 15 to rest on said chest and provided with a lug depending in front of said lug on said valve casing, a keeper engaging member pivoted on said clip bar to engage said keeper and the rear side of said chest, and a screw 20 disposed through said lug on said clip bar to engage said valve casing lug, whereby said pneumatic is detachably secured to said suction chest.
- 25 2. In a structure of the class described, the combination with a suction chest having a port in its front side, of a pneumatic comprising a relatively fixed member disposed below said chest and having thereon a keeper, a valve casing secured to said pneumatic and 30 disposed on the front side of said chest and provided with a port registering with the said port thereof, a clip bar disposed to rest on said chest, a keeper engaging member pivoted on said clip bar to engage said keeper 35 and the rear side of said chest, and a clamping screw disposed on said clip bar to engage said valve casing whereby said pneumatic is detachably secured to said suction chest.
- 40 3. In a structure of the class described, the combination of a suction chest, of a pneumatic disposed below said chest and provided with a valve casing disposed against the front side thereof, said pneumatic being 45 provided with a keeper disposed at the rear of said chest, and a securing means for said pneumatic comprising a pair of pivotally connected members one of which is disposed to engage said keeper and the rear side of 50 said chest and the other to engage the top of said chest, and a clamping screw on the second of said members engaging said valve casing.
- 55 4. In a structure of the class described, the combination with a suction chest, of a pneumatic provided with a keeper and having a valve casing disposed against said chest, and a securing means for said pneumatic comprising a pair of pivotally connected members disposed to engage said chest, one of 60 said members engaging said keeper and the other being provided with a clamping screw engaging said valve casing.
- 65 5. In a structure of the class described, the combination with a suction chest of a pneumatic, a valve casing rigidly secured to the upper member thereof, and having an upwardly projecting lug, a keeper on the 70 said member, a clamp comprising a horizontal member adapted to contact with the upper side of the suction chest, and a lever member with a projecting toe to engage said keeper, and a downwardly depending lug on the horizontal member with a set screw for 75 engaging the lug on the valve casing, coacting for the purpose specified.
- 80 6. In a structure of the class described, the combination with a suction chest of a pneumatic, a valve casing rigidly secured to 85 one side of said pneumatic, a clamp comprising a member engaging one side of a suction chest and a lever pivoted to said member engaging the side of the suction chest opposite the valve casing and a keeper on the pneumatic, all coacting for the purpose specified.

In witness whereof, I have hereunto set my hand and seal in the presence of two witnesses.

WALTER LANE. [L. S.]
